ADJUSTABLE SEWING MACHINE FEED

Joseph Gottlieb, Jersey City, Carl Woessner, Bloomfield, and Ludwig Eickemeyer, Union, N. J., assignors to Gibraltar Manufacturing Co., Inc., Jersey City, N. J., a corporation of New Jersey

Application September 28, 1949, Serial No. 118,272

6 Claims. (Cl. 112—210)

1

This invention relates to a sewing machine, and more particularly, to means for operating the cloth feed dog of a sewing machine.

In the usual domestic sewing machine, there is found a cloth feed dog formed generally as a serrated member that is actuated cyclically to contact and move the cloth. It has been found desirable to adjust the distance that the feed dog moves the cloth during each of its cyclic strokes, and further, the adjusting means are usually adapted to determine the direction of the feed movement of the dog so that the cloth may be moved in either of opposed directions relatively to the needle of the machine.

It is the object of our invention to contribute to the art an extremely simple and inexpensive means for actuating the cloth feed dog of a sewing machine, and for controlling both its direction of movement and the distance through which it moves the cloth during each operating cyclic stroke. It is the further object to actuate the feed dog in exact timed relation to the remainder of the machine.

As a feature of our invention, we utilize a feed dog that is adapted particularly for actuation by means operated from a single shaft of the machine. In this way, it becomes quite simple to co-ordinate movements of the feed dog relatively to the remainder of the machine. As a further feature of this part of the invention, the feed dog is actuated simultaneously by two mechanisms, with one mechanism moving the dog horizontally or in a cloth moving direction, while the other mechanism moves the dog into and out of the plane in which the cloth is actuated.

As a particularly important feature of our invention, we use a reciprocating actuator for the feed dog, with means for varying the axis of reciprocation of the dog actuator, and by operating the feed dog in every axis of reciprocation of the actuator except a neutral axis, we can vary the direction of movement of the feed dog while also varying the amplitude of movement thereof by the actuator.

More particularly, as a feature of our invention, we arrange for guide means to guide the actuator so that through movement thereof into different angular positions relatively to an operating shaft, the actuator is reciprocated in various axes. As a further particular feature, we use simple cam means, that preferably take the form of a pin and slot connection, for guiding the actuator and to move the feed dog varying amplitudes during each cycle, and in varying directions in each cycle relatively to the remain-

ing operating parts of the machine, all as will appear presently.

We have thus outlined rather broadly the more important features of our invention in order that the detailed description thereof that follows may be better understood, and in order that our contribution to the art may be better appreciated. There are, of course, additional features of our invention that will be described hereinafter and which will form the subject of the claims appended hereto. Those skilled in the art will appreciate that the conception on which our disclosure is based may readily be utilized as a basis for the designing of other structures for carrying out the several purposes of our invention. It is important, therefore, that the claims to be granted us shall be of sufficient breadth to prevent the appropriation of our invention by those skilled in the art.

Referring now to the drawings, Fig. 1 is an elevation of a sewing machine embodying my invention, with certain parts thereof cut away to illustrate the parts. Fig. 2 is a view looking upwardly from the bottom of the machine of Fig. 1. Fig. 3 is a section taken along lines 3—3 of Fig. 2. Fig. 4 is a section taken along lines 4—4 of Fig. 1. Figs. 5 and 6 are sections taken respectively along lines 5—5 and 6—6 of Fig. 1. Fig. 7 is a view of the front end of the lower part of the machine. Fig. 8 is a perspective view of the lower part of the actuator and illustrates its relation to the guide means therefor and the feed dog operating means.

Referring now more particularly to the drawings, and especially to Figs. 1 and 4, reference numeral 10 indicates the upper shaft of a standard type domestic machine that we shall hereinafter refer to as a main operating shaft. Shaft 10 in the usual machine will actuate any usual take-up mechanism located at the head of the machine designated by reference numeral 11. Shaft 10 of our machine has secured at its right hand end a hand wheel 12 and a pulley 13 whereby it may be driven by an electric motor or by pedal power through a usual form of leather belt.

Secured to the shaft 10 just inwardly of the casing 14 of the machine is an eccentric 15. Eccentric 15 is embraced by the arms 16 and 17 of a lever 18 pivoted at 19 to the casing of the machine and extending downwardly through an opening 20 in the base plate 21 of the machine. The downwardly extending end of the lever 18 is bifurcated to form arms 22 that embrace a ball 23 secured at the right hand end of a shuttle carrying lever 24 pivoted at 25 to the base plate

21. At the extreme left hand of the lever 24, as best seen in Fig. 2, there is mounted shuttle mechanism 26 of a standard type well known in the art. It is the function of the lever 18 to reciprocate the arm 24 and the shuttle 26 during the sewing operation, this reciprocation taking place in timed relation to the rotation of the shaft 10 and the take-up mechanism in the head 11 that is actuated by the shaft 10.

The feed dog assembly of our sewing machine, best seen in Fig. 7, is designated generally by reference numeral 30 and comprises a bar 31 to which is secured a serrated or ratcheted feed dog 32 through a screw stud 33. Lever 31 is formed with a slot 34 mounted about the bearing stud portion 35 of a screw stud 36, the screw stud 36 being itself screwed to a vertical bracket 37 extending downwardly from the base plate 21.

As is well shown in Figs. 3 and 7, a further bracket 38 is secured to the plate 21, this bracket being formed with an opening 39 into which extends the end 40 of an actuator bar 41. The end 40 of the actuator bar 41 lies not only within the opening 39 of the bracket 38, but also within a slot 42 of the feed dog bar 31. Actuator bar 41 is pivoted at 43 to an arm 44 of the shuttle lever 24, and during rotary reciprocation of the shuttle lever 24, the actuator bar 41 will move inwardly and outwardly of the opening 39 in the bracket 38. This movement of the actuator bar 41 will, through a cam portion 45 of the said bar 41, effects the pivotal movement of the bar 31 relatively to the stud shaft 35. Thus, as the bar 41 is moved to the left in Figs. 2 and 3 incidental to clockwise rotation of the shuttle lever 24, it effects the rotation of the bar 31 in one direction about the stud 35, while the return movement of the shuttle lever 24 will be accompanied by a reverse pivotal movement of the bar 31. This motion of the bar 31 by the actuator bar 41 moves the feed dog 32 into and out of a position just above the upper surface of the plate 21. Naturally, when the dog 32 is above the upper surface of the plate 21, it is in contact with cloth applied to the said plate and will act to move the cloth relatively to the needle of the machine. Contributing to the tractive effect exercised by the dog 32 is a presser foot P which bears against the cloth to apply it to the teeth of the dog 32 whereby to be moved by those teeth, all as those skilled in the art will fully appreciate.

Referring now back once again to Figs. 1 and 4, a further eccentric 50 is secured to the main shaft 10 of the machine, and embracing the eccentric 50 are upper and lower arms 51, 52, of an actuator lever 53. Opposed to the lower arm 52 of the actuator lever 53 is a further lower arm 54, it being the function of the arms 52 and 54 to guide the lever for reciprocating movement relatively to the casing of the machine while allowing limited rotation of the lever so as to place the surfaces 51a and 52a thereof into different angular relationships to the eccentric 50.

Obviously, when the actuator lever 53 is in different rotated positions relatively to eccentric 50, it is reciprocated by the eccentric 50 through its contact with surfaces 51a, 52a, in different axes angularly spaced relatively to the axis of shaft 10.

For determining the angular position of the actuator lever 53 with respect to the eccentric 50, and thereby determining the axis of reciprocation thereof, the lower end of the actuator lever 53 is equipped with a roller 55 carried by a pin 56 that extends transversely through the

lever 53 as best seen in Figs. 4, 5, 6, and 8. Roller 55 is adapted to rest within the groove of a channel 57, channel 57 forming itself part of an adjustment assembly 58 that is pivoted to a bracket 59 on a pivot shaft 60. A friction washer 61, whose tension is adjusted by a screw 62, tends to hold the adjustment assembly 58 in any position to which it is rotated by a finger piece 63 forming an integral part thereof. Finger piece 63 moves relatively to a dial 64 marked with suitable numerals to indicate direction of feed movement of the feed assembly 30 and the amplitude of movement of the feed dog 32 in each feed cycle.

Pin 56, on which is mounted roller 55, carries a further roller 70 that bears within the groove of channel 71 of a slide 72 that is carried on the plate 21 by a pair of bearing studs 73, all as best seen in Figs. 5, 6 and 8. Pivoted to the slide 72 at 74 is a lever 75 that is in turn pivoted to the plate 21 at 76. Lever 75 terminates at its left end in Figs. 1 and 2 in a small extension 77 fitting into a slot 78 of the bar 31. It will be appreciated that the end of lever 75, pivoted to slide 72 at 74, will move in an arc while the slide 72 moves linearly. However, the radius of the arc is so great relatively to the extent of movement of the lever 75 and the slide 72, that the normal tolerances of the parts will allow them to move freely in the manner set forth.

As the actuator lever 53 reciprocates upwardly and downwardly in Figs. 4 and 5, it will not effect movement of slide 72 when channel 71 is parallel to the axis of reciprocation of the lever 53 and co-extensive with the axis of reciprocation of the pin 56 and roller 70. Thus, if in Fig. 5 the roller 70 and pin 56 move vertically within the channel 71 and in alignment with the axis of channel 71, there will be no corresponding movement of the slide 72 to the right or left in that figure. Therefore, there will be no movement of the lever 75 and no reciprocating feed movement of the feed mechanism 30 and dog 32. When the finger piece 63 is in a position opposite N of the dial 64 in Fig. 1, the axis of reciprocation of the actuator lever 53 will be such that rollers 55, 70 and pin 56 will move in axial alignment with channel 71. Thus, with the finger piece 63 in the N or neutral position, there will be no movement of the feed dog 32 and any cloth applied to the machine and under the presser foot P will not be moved in a feed direction.

When the finger piece 63 is moved in one direction or another from the neutral position N, the axis of reciprocation of the actuator lever 53 relatively to the vertical will be changed because of the new alignment of channel 57 relatively to roller 55, and then more or less movement of the slide 72 will be effected by the roller 70. If we suppose, for example, the axis of reciprocation of the pin 56 in Fig. 5 is along the line 80, then it is obvious that a relatively considerable movement of the slide 72 will take place, with the direction of movement consequently imparted to dog 32 being in predetermined relation to the pivotal movement of the bar 31 and the dog 32 about the stud 35. If, on the other hand, the axis of reciprocation is effected along the line 81 in Fig. 5 by finger piece 63, then there will be a considerable throw of the feed dog 32 but in an opposite relation to the movement of the bar 31 by the actuator bar 41. Therefore, it is possible through changing the axis of reciprocation of the actuator lever 53 to vary the direction of horizontal movement of the feed dog 32 relatively to its upward and downward move-

ment and to vary the directional motion of any cloth applied under the presser foot P. It is also possible to change the amplitude of movement, all as will be quite apparent.

Those skilled in the art will now understand that the actuation of the cloth feed mechanism is, through our invention, accomplished in an extremely simple manner and in accurately timed relation to the remaining parts of the machine.

We now claim:

1. In a sewing machine of the class described, a main rotating shaft, an eccentric on said shaft, an actuator in engagement with said eccentric whereby rotation of said eccentric reciprocates said actuator, a pin on said actuator, a guide comprising a slotted member in which a part of said pin is mounted, means for moving said guide whereby to rotate said actuator relatively to said eccentric to determine the axis of reciprocation of said actuator, a feed dog, a feed slide for actuating said feed dog, means mounting said feed slide for sliding movement in a predetermined axis, a slotted member formed as an integral part of said feed slide, and a part of the said pin moving in the slot of said slotted member for reciprocating the feed slide when the axis of reciprocation of said actuator is angular to the axis of said slot.

2. In a sewing machine of the class described, a main rotating shaft, an eccentric on said shaft, an actuator having parallel spaced surfaces embracing said eccentric whereby rotation of said eccentric reciprocates said actuator through said surfaces, a pin on said actuator, a guide comprising a slotted member in which one end of said pin is mounted, means for moving said guide whereby to rotate said actuator relatively to said eccentric to determine the axis of reciprocation of said actuator, a feed dog, a feed slide for actuating said feed dog, means mounting said feed slide for sliding movement in a predetermined axis, a member formed as a part of said feed slide and having a slot extending at right angles to said predetermined axis, and a part of said pin moving in the slot of said member for reciprocating the feed slide when the axis of reciprocation of said actuator is angular to the axis of said slot.

3. In a sewing machine of the class described, a main rotating shaft, an eccentric on said shaft, an actuator in engagement with said eccentric whereby rotation of said eccentric reciprocates said actuator, means for rotating said actuator into different angular positions relatively to said eccentric whereby to determine the reciprocating axis of said actuator, a feed dog, a feed slide for reciprocating said feed dog, means mounting said feed slide for sliding reciprocating straight line movement, means whereby said actuator reciprocates said feed slide when said actuator moves in a reciprocating axis at an angle to a predetermined neutral axis of reciprocation for imparting reciprocating movement to said feed dog, and additional means extending between said shaft and feed dog for moving said feed dog transversely relatively to its reciprocating path.

4. In a sewing machine of the class described, a main rotating shaft, an eccentric on said shaft, an actuator in engagement with said eccentric whereby rotation of said eccentric reciprocates said actuator, means for rotating said actuator into different angular positions relatively to said

eccentric whereby to determine the reciprocating axis of said actuator, a feed dog, a feed slide for reciprocating said feed dog, means mounting said feed slide for sliding movement in a predetermined line, a pin and slot connection between said feed slide and actuator whereby said actuator reciprocates said feed slide except when the axis of reciprocation of said actuator is parallel to the axis of said slot, the axis of said slot being at right angles to said predetermined line of reciprocation of said feed slide, and additional means extending between said shaft and feed dog for moving said feed dog transversely relatively to its reciprocating path.

10 5. In a sewing machine of the class described, a main rotating shaft, an eccentric on said shaft, an actuator in engagement with said eccentric whereby rotation of said eccentric reciprocates said actuator, a pin on said actuator extending to each side thereof, a guide comprising a slotted member in which one end of said pin is mounted, means for moving said guide whereby to rotate said actuator relatively to said eccentric to determine the axis of reciprocation of said actuator, a feed dog, a slotted member for reciprocating said feed dog, means mounting said slotted member for sliding movement in a predetermined axis with its slot at right angles to said predetermined axis, the other end of said pin moving in the slot of said slotted member for reciprocating the feed dog when the axis of reciprocation of said actuator is angular to the axis of said slot, and additional means extending between said shaft and feed dog for moving said feed dog transversely relatively to its reciprocating path.
